Patented Nov. 21, 1922.

Inventor
Louis G. Miller.

By Geo. E. Thackray
Attorney

UNITED STATES PATENT OFFICE.

LOUIS G. MILLER, OF WESTMONT BOROUGH, PENNSYLVANIA.

TRUCK BOLSTER.

Application filed January 26, 1922. Serial No. 531,973.

To all whom it may concern:

Be it known that I, LOUIS G. MILLER, a citizen of the United States, and a resident of the borough of Westmont, county of Cambria, and State of Pennsylvania, have invented certain new and useful Improvements in Truck Bolsters; and I do hereby declare the following to be a full, clear, and exact description of the invention, such as

10 will enable others skilled in the art to which it appertains to make and use the same.

My invention relates to bolsters preferably formed of pressed steel and of what is known as the bath-tub type, and comprises 15 the construction of the end portions of a bolster which are made of a width sufficient to accommodate five or six helical springs of a large and heavy type such as are used with large capacity cars, and to accomplish this 20 the end portions of the bolster which bear directly or indirectly upon the springs are made wider, so that the required number of springs can be placed under each end of the bolster to meet the requirements of use with 25 heavy loads.

Bolsters of this type heretofore made have had their webs substantially parallel, so that the end width of the bolster proper was comparatively narrow and could not accommodate 30 five or more springs of the required size, whereas I spread the parallel webs at their end portions so that the ends are wider than heretofore for the purposes mentioned.

The body portion of the bolster is of the 35 usual bath-tub type, consisting of a U-shaped section, preferably formed of metal, deeper at its center than at its ends and with a cover plate riveted to its outstanding integral top flanges and provided with the usual center plate, diaphragm and side bearings secured thereto.

Although my invention is applicable to bolsters of the bath-tub type, which are deeper at the center than at the ends, I wish 45 it understood that the invention may also be applied to bolsters which are of substantially uniform depth throughout.

Having thus given a general description of my invention, I will now, in order to 50 make the matter more clear, refer to the annexed sheet of drawings, which form part of this specification, and in which like characters refer to like parts:—

Figure 1 is a top plan view of my improved 55 truck bolster; Figure 2 is a side elevation of

the bolster shown in Figure 1; Figure 3 is an end elevation of the end only of the bolster shown in Figures 1 and 2; Figure 4 is a top plan view showing the end of a slightly modified form of bolster; Figure 5 is an elevation of the end only of the modified form of bolster in Figure 4, and Figure 6 is a side elevation of the end of the modified form of bolster shown in Figures 4 and 5.

Referring now to the characters of reference on the drawings:—1 is the main body of the bolster consisting of two web plates which are substantially parallel in their intermediate and end portions with an abruptly inclined connecting web portion 6 60 and are connected by an integral lower member as illustrated, while the upper edges of the intermediate portions of the webs are provided with flanges 2 extending outwardly therefrom and secured together by 65 the top cover plate 3 riveted thereto. The customary center plate 4 is also secured on the top of the bolster at its center, and the usual side bearings 5 are also provided, secured to the top of the bolster at suitable 70 locations as illustrated. At the ends of the bolster I bend the webs outwardly in some- 75 what abrupt manner as illustrated at 6, so that the parallel end portions of the webs are approximately the same or a little less 80 in width than the overall width of the bolster cover plate. The intermediate portion of my bolster is of substantially uniform 85 width but of a width sufficient so that it is amply strong to withstand any lateral 90 stresses to which it is subjected, owing to the longitudinal movement of the car body thereon. The end portions of my bolster have an integrally formed spring seat 7, under which are mounted the coil springs 8, of 95 which I provide five at each end as indicated by dotted lines in Figure 1. These springs are preferably duplex and grouped in nests of five and provided with comparatively thin top and bottom plates and are secured together in nests by means of a central bolt (not shown). I also provide column guides 100 secured to the sides of the bolster end by rivets 9, and as illustrated in Figures 1, 2 and 3 I provide diagonally inclined reinforcing brackets 11 at each end of the bolster, provided with flanged edges 12, through which they are secured to the sides of the bolster ends by rivets as illustrated. The cover plate 3 is provided with down- 105

110

wardly bent ends 13, which are inclined to the same extent as the body portions of the reinforcing brackets 11, and the reinforcing brackets are secured thereto by the rivets 14 5 as shown.

In order to further strengthen and stiffen each reinforcing bracket I provide a pressed rib or corrugation 15 at its central portion. It should also be noticed that this reinforcing plate 11 has its lower edge riveted to the outer edge of the wider portion of the integral bottom member 7 of the bolster, forming the spring seat, as particularly illustrated in Figures 1 and 3. These reinforcing members, by reason of their construction and position, form extensions to the body of the bolster within its end from near the insides of the column guides to the outer edges of the bolster end, and they 10 therefore serve to strengthen and stiffen the construction to more properly carry the load to which it is subjected.

The abrupt widening of the bolster also provides a corresponding widening of the bottom bolster member at its ends, which makes the integral spring seats 7 of a width sufficient to each accommodate five or six helical springs for the largest types of cars having capacities up to one hundred tons, 15 and the bolster is at the same time integral and its intermediate width and strength are similar to prior bolsters of this type, the differences being in the end construction for the purposes mentioned.

Referring now to Figures 4, 5 and 6, these illustrate a slightly modified form of reinforcing plate for the bolster ends, which consists of a casting 16, which is of the shape shown and provided with flanges 20 whereby it is secured to the bolster end by rivets 17, and the end of the cover plate 18 is also secured to this casting by means of the rivets 19. A space is provided in the web of the casting 16 so that access may be 25 had to the rivet heads 19 for the purpose of driving them, and as viewed in plan, the casting 16 is similar in shape to an I-beam.

The column guides 10 may be either rolled or cast and are preferably provided 30 with integral ribs as illustrated to prevent undue longitudinal movement of the bolster, and these ribs with the flat portions between them form the column guides and rest against the truck columns to guide the 35 bolster in its up and down movement on the springs.

Although I have shown and described my invention in considerable detail, I do not wish to be limited to the exact and specific 40 details thereof as shown and described, but may use such modification in, substitutions for, or equivalents thereof as are embraced within the scope of my invention, or as pointed out in the claims.

Having thus described my invention,

what I claim and desire to secure by Letters Patent is:—

1. A truck bolster, the body portion of which is provided with two substantially parallel webs, a bottom portion connecting the same, all formed integrally, the webs at the ends being abruptly bent outwardly, the ends of the bottom portions thus forming wide spring seats. 70

2. A truck bolster, the body portion of which intermediate of its ends is formed with two webs substantially parallel and spaced apart, the webs near the end portions being bent outwardly and spaced apart a greater width than the intermediate portions, and a bottom member integrally connecting said webs, thus forming wider spring seats at the bolster ends. 80

3. A truck bolster of the bath-tub type, the portion between the ends having parallel webs which are bent outwardly at the end portions, and an integral bottom plate connecting said webs, thus forming wider integral spring seats, a top cover plate secured to the outstanding flanges of the webs, 90 the ends of which are bent downwardly at an inclination, and a reinforcing member secured thereto and with flanged edges secured to the ends of the bolster webs. 98

4. A bolster of the class described, the intermediate portion having a pair of webs spaced apart and substantially parallel, and wider integral end portions, a reinforcing member inclined downwardly from the inner top portion of each end within the same 100 and secured thereto. 105

5. A truck bolster, the intermediate portion of which comprises a pair of webs spaced apart, a bottom member connecting said webs, and end portions wider than the intermediate portion, all formed integral, thereby providing wider spring seats, and a reinforcing member arranged within the ends of the bolster, inclining downwardly and secured therein. 110

6. A truck bolster, the intermediate portion of which comprises a pair of webs spaced apart, a bottom member connecting said webs, and end portions wider than the intermediate portion, all formed integral, thereby forming wider spring seats, an inclined reinforcing member secured within each end of the bolster, and column guides secured to the ends of the webs. 115

7. A truck bolster, the intermediate portion of which comprises a pair of webs spaced apart, upper flanges projecting outwardly therefrom, a bottom member connecting said webs, with end portions wider than its intermediate portion, all formed integral, thereby forming wider spring seats, an inclined reinforcing member secured within each end of the bolster, and a top cover plate secured to said flanges and reinforcing member. 120

8. A truck bolster of the class described, comprising an intermediate portion with a pair of substantially parallel webs spaced apart, upper flanges projecting outwardly therefrom, a bottom member connecting said webs with its end portions wider than its intermediate portions, the webs adjacent the inner part of the end portions extending outwardly in an abrupt manner, all formed integrally, thereby providing wider end portions forming spring seats, a top cover plate secured to said flanges and having its end portions projecting in an inclined manner within the end portions of the bolster, a pan-shaped reinforcing plate within each end of the bolster, with its upper edge secured to the cover plate, its lower edge secured to the bottom member and its flanges secured to the end portions of the webs. 5
9. A bolster of the bath-tub type with integral outwardly extending flanges, having an integral end portion forming the spring seat, the lower surface of which is of a width substantially equal to that of the upper part of the bolster body between the outer edges of said flanges. 10
10. A bolster of the bath-tub type with integral outwardly extending flanges, the end portion forming the spring seat of which is formed integrally of a width substantially equal to that of the upper portion of the bolster adjacent said end portion between the outer edges of said flanges. 15
11. A bolster of the bath-tub type, the integral end portions of the webs of which are spaced apart a distance greater than the substantially parallel intermediate portions thereof, thereby providing an integral spring seat of a width greater than the other lower portion of the body of the bolster. 20
12. A bolster of the bath-tub type, the integral end portion of the webs of which are joined by the bottom member and spaced apart a distance greater than the substantially parallel intermediate portions thereof, thereby providing an integral spring seat of greater width. 25
13. A bath-tub type of bolster, the body portion of which is formed integrally with the two webs spaced apart, outwardly projecting upper flanges and an integral lower member, the ends being of a width substantially equal to that of the over-all width of the flanges, thereby providing an integral wide spring seat. 30
14. A bath-tub type of bolster, the body portion of which is formed integrally with two webs spaced apart, upper outwardly projecting flanges and an integral lower member joining said webs, the end portions being of a width substantially equal to that of the upper portion of the body of the bolster, thereby providing an integrally formed wide spring seat, and column guides secured to said end portions. 35
15. A bolster having a pair of webs spaced apart and joined by a lower member, the end portions of the web being a greater distance apart than the substantially parallel intermediate portions, the end portions of the lower member having a greater width than the intermediate portion thereof, thereby providing an integral wide spring seat. 40
16. A bolster having a pair of web portions spaced apart and joined by an integral lower member, said webs having integral outwardly projecting upper flanges extending from their intermediate portions and joined by a cover plate secured thereto, the end portions of the web being spaced apart a greater distance than the substantially parallel intermediate portions thereof, and the end portions of the lower members being of a greater width than the intermediate portion, thereby providing a wide spring seat. 45
17. A bolster comprising a pair of web portions spaced apart and joined by an integral lower member, the webs having outwardly projecting upper flanges intermediate of the ends, with a cover plate secured thereto, the ends of said web portions being of a width substantially equal to the overall width of the outwardly projecting flange portions, and the lower member of a corresponding width, stiffeners secured within the end portions and column guides mounted on and secured to the sides of the end portions. 50

In witness whereof I hereunto affix my signature.

LOUIS G. MILLER.
